Primary Examiner — R. Johnson

(57) **CLAIM**

The ornamental design for a guitar capo, as shown and described.

DESCRIPTION

FIG. 1 is a perspective view of a guitar capo showing my new design.

FIG. 2 is a front view of a guitar capo.

FIG. 3 is a rear view of a guitar capo.

FIG. 4 is a left side view of a guitar capo.

FIG. 5 is a right side view of a guitar capo.

FIG. 6 is a top view of a guitar capo.

FIG. 7 is a bottom view of a guitar capo.

FIG. 8 is a rear side perspective view of a guitar capo.

FIG. 9 is an enlarged detail view of area 9 shown in FIG. 3.

FIG. 10 is an enlarged detail view of area 10 shown in FIG. 4; and,

FIG. 11 is an enlarged detail view of area 11 shown in FIG. 5.

The broken lines in the drawings depict portions of the guitar capo that form no part of the claimed design.

1 Claim, 11 Drawing Sheets
